UNITED STATES PATENT OFFICE.

ROBERT C. ANGELL, OF PRINCE BAY, NEW YORK, ASSIGNOR TO THE S. S. WHITE DENTAL MANUFACTURING COMPANY, A CORPORATION OF PENNSYLVANIA.

BRACKET-TABLE.

1,324,370.

Specification of Letters Patent.

Patented Dec. 9, 1919.

Application filed November 27, 1915. Serial No. 63,722.

To all whom it may concern:

Be it known that I, ROBERT C. ANGELL, a citizen of the United States, and a resident of Prince Bay, in the county of Richmond, 5 State of New York, have invented certain new and useful Improvements in Bracket-Tables, of which the following is a specification, reference being had to the accompanying drawings.

10 My invention relates particularly to that class of bracket tables that are designed for the use of professional operators, such as dentists, etc., and is especially directed to the construction of the bracket upon which the 15 table is supported.

The principal objects of my invention are, to provide a table bracket with means to adjustably secure a table top, preferably formed of vitreous or ceramic material, in 20 readily detachable relation therewith.

Other objects of my invention are, to provide a table bracket with means for detachably supporting a burner so formed that the 25 gas connection may be effected beneath the table top while the burner is conveniently disposed above said table top.

Specifically stated, my invention comprehends a bracket arm rotatably supporting a spider frame, having means on its arms 30 for engaging an undercut boss on the under side of the table top.

My invention also includes all of the various novel features of construction and arrangement hereinafter more definitely specified.

In the accompanying drawings, Figure 1 is a plan view of a bracket table constructed in accordance with my invention, showing fragmentary outlines of the table top in dot 40 and dash lines, for convenience of illustration; Fig. 2 is a central vertical sectional view of said bracket table, taken on the line 2-2 in Fig. 1; Fig. 3 is a central vertical sectional view, similar to Fig. 2, taken on 45 the line 3-3 in Fig. 1; and Fig. 4 is an elevational view of the clamp shown in Fig. 3, as viewed from the right of said figure.

In said figures, the supporting bracket arm 5, which may be suitably mounted in 50 any well known manner, is provided at its free end with a bearing 6 in which the tapering shaft or post 7 of the table supporting spider 9 is rotatably supported.

The spider 9 comprises a plurality of radially extended arms 10, 11 and 12, respec-

tively having raised seats 13, 14 and 15 for the table top 16, which may be of any desired material, but preferably of glass.

The table top 16, as shown in Figs. 2 and 3, may be provided with the upwardly extending peripheral flange 17 to prevent articles laid thereon from being accidentally brushed therefrom, and has the depending annular boss 19 whose outer walls conform to the curved surface of a conical frustum 60 and thereby provide an undercut retention, which, as best shown in Fig. 2, is arranged to be engaged by inwardly projecting fingers 20 and 21 formed by projections extending upwardly and inwardly from the respective 65 arms 10 and 11 and by the finger 22 on the clamp 23, which is arranged to rock upon the arm 12 and to be adjusted with respect to said boss by the thumb-screw 24.

As best shown in Figs. 3 and 4, the clamp 75 23 has its lower end bifurcated to form prongs 25 and 26, which straddle the single prong 27 projecting outwardly from a depending lug 29 on the arm 12, and which are arranged to rock upon the surfaces 30 of said 80 lug which extend laterally from the prong 27 in a plane preferably inclined downwardly toward the axis of rotation of the table.

The clamp 23 is provided with an aperture 32 disposed centrally therein, through which 85 the thumb-screw 24 may loosely extend with its threads in threaded engagement with the threaded socket 33 in the arm 12, and with the spherical surface 35 of the head 36 seated in the spherical seat 37 surrounding the 90 aperture 32.

In order that the table supporting spider 9 may be interchangeable with bracket arms having different sizes or forms of bearings, the shaft or post 7 may be removably engaged in the hub of the spider by the set-screw 39, as shown in Fig. 2, so that other shafts or posts may be replaced therefor, corresponding with the size or form of the bearing in the bracket arm to which it is desired that the table shall be attached.

The arm 11 supports the gas burner 40 independently of the table top 16, and has the socket 41 into which the burner fitting 42 may be engaged by the set-screw 43. Said 105 burner fitting 42 is provided with an inlet nipple 45 to which the gas supply conveyer (not shown) may be readily attached, and is connected with the burner 40 by the burner tube 46 which extends radially out- 110

ward beneath the table, having a return bend or bight 47 around the edge of the table and extending radially inward and supporting the burner at a suitable distance over and independently of said table as best shown in Fig. 2.

My invention is advantageous in that while the table is rigidly held without possibility of accidental displacement from its support, it may by a slight adjustment of the clamp 23 be readily removed from said support without in any way disturbing the burner or severing the connection with the fluid supply.

I do not desire to limit my invention to the precise details of construction and arrangement herein set forth, as it is obvious that various modifications may be made therein without departing from the essential features of my invention as defined by the appended claims.

Having thus described my invention, I claim:

1. A bracket table, comprising a table top having an undercut depending boss, a spider frame provided with a pivoted shaft or stud, and having arms supporting said table top and carrying projecting fingers arranged to engage the undercut surface of said boss, one of said fingers being arranged to rock upon its arm and having means arranged to adjust it into and out of engagement with said undercut surface.

2. A bracket table, comprising a table top, a frame having a plurality of arms, a removable shaft for said frame arranged to be rotatably supported, a bracket having a bear-

ing for said shaft, and a clamp having its end bifurcated to form prongs arranged to straddle one of said arms, and adjustable to secure said table top to said frame.

3. A bracket table, comprising a table top having an undercut boss, a spider frame arranged to be adjustably supported and having projecting fingers overhanging said undercut boss, a clamp adjustable to engage said fingers with said boss, and a burner having a fuel conveyer detachably supported by said spider frame independently of the table.

4. A bracket table, comprising a table top having an undercut depending boss, a spider frame arranged to be rotatably supported and having projecting fingers overhanging said undercut boss, a clamp adjustable to engage said fingers with said boss, and a burner removably supported by said spider independently of the table top and disposed above said table top, and supplied with fuel from beneath said table.

5. A bracket table, comprising a table top, a frame beneath said table top, and a burner disposed above the table top and carried by said frame independently of said table top, the connection between said burner and frame comprising a hollow member serving to convey fuel to said burner.

In witness whereof I have hereunto set my hand this 24th day of November, A. D. 1915.

ROBERT C. ANGELL.
